(57) **CLAIM**

The ornamental design for a transfer cross member, as shown and described.

DESCRIPTION

FIG. 1 is a top plan view of a transfer cross member;

FIG. 2 is a front elevational view thereof;

FIG. 3 is a bottom view thereof;

FIG. 4 is a left elevational view thereof;

FIG. 5 is a rear elevational view thereof;

FIG. 6 is a right elevational view thereof; and,

FIG. 7 is an isometric view thereof.

The broken lines are for environmental purposes only and form no part of the claimed design.

The claimed transfer cross member is used to support a vehicle transmission assembly.
